UNITED STATES PATENT OFFICE.

JOSHUA O. HOWE, OF BLOOMINGTON, INDIANA, ASSIGNOR OF ONE-THIRD
TO S. BROWN WYLIE, OF SAME PLACE.

LIGHTING DEVICE.

SPECIFICATION forming part of Letters Patent No. 375,632, dated December 27, 1887.

Application filed April 13, 1887. Serial No. 234,715. (No model.)

To all whom it may concern:

Be it known that I, JOSHUA O. HOWE, a citizen of the United States, and a resident of Bloomington, Indiana, have invented certain 5 Improvements in Automatic Fire-Lighting Devices, of which the following is a specification.

The object of my invention is to construct a simple form of automatic fire lighter, which is 10 more especially adapted for use in connection with steam fire-engines.

In the accompanying drawings, Figure 1 is 15 a view showing the manner in which my automatic fire-lighter is adapted to be used in connection with a steam fire-engine. Fig. 2 is a vertical section, drawn to an enlarged scale, of my fire-lighter; and Fig. 3 is a plan view of the same.

A is an open pan or dish, which may be of 20 any suitable form, and which in the present instance is shown as of round shape, to correspond with the grate of a fire-engine. This pan is for the reception of shavings or other suitable combustible material, and it is provided in its bottom with a number of air tubes or openings, *a*, for the admission of air to support combustion when the material is ignited, as hereinafter described. On the under side of the pan is a box or bracket, B, containing 25 a spring, D, which in the present instance is spiral, and is connected at its outer end to the box or bracket and at its inner end to a central axis, F. This axis F has a bottom or step bearing in the box or bracket B, and a bearing 30 in a sleeve, *f*, carried by or forming part of a pan, B. This central axis has at its upper end an arm, G, which carries a match-holder, *g*, and which is adapted to engage with and be held by a bolt or catch, H, sliding in a bracket, 35 *h*, carried by the pan. The position of this retaining-catch may be that shown by full lines, or that shown by dotted lines in Fig. 2, as convenience may require.

I secure to the inside of the pan a yielding 45 striking-surface for matches, and in the present instance I have shown this striking-surface as composed of a curved spring-plate, S, which is fastened at one end to the pan and at the other end is free. This free end of the plate 50 has a roughened face, as shown in Figs. 2 and

3, lying in the path of the matches as they are carried round by the supporting-arm when the central axis is rotated. I provide in addition a bracket, K, on the inside of the pan, to support a glass or other breakable bottle, *k*, containing benzine or other suitable combustible fluid. On the arm G there is secured a roughened or toothed projection, P, which, when the central axis and arm are rotated by the spring, comes into contact with and breaks the bottle, 60 to thereby distribute the fluid over the combustible material in the bottom of the pan.

When this fire-lighter is to be used in connection with a steam fire-engine, as illustrated in Fig. 1, it is mounted on a suitable support, 65 M, secured to the wall or floor of the engine-house in such a position that when the engine is backed into the engine-house the fire-lighter will be immediately under the grate. This support may be in the form of legs M, preferably secured to the floor, or it may be a bracket, M', secured to the wall. It is preferable to make a part of the support hinged or otherwise adjustable, to allow the lighter to be moved to different positions. The catch or bolt H is 70 provided with a cord, wire, or chain passing over pulleys, and may be automatically withdrawn by suitable connections with electric-alarm apparatus, or by the opening of the horse-stall door or doors, or opening of engine-house door or doors, or by a hand-pull or other means. When the bolt H is withdrawn, it releases the arm G, so that the latter is rapidly swung round under the action of the springs, the matches strike against the prepared surface to ignite the combustible material in the bottom of the pan, and the flame is increased by the fluid from the bottle *k*, which is then broken by the projection P. A fire 75 being thus lit under the surface of the grate 80 of the engine, the ignition of the fuel in the fire-box will have been well started by the time the engine moves out.

Although I have devised my improvements more especially for use in connection with fire-engines, it should be understood that they may be employed equally well for the automatic lighting of any fire.

I claim as my invention—

1. The combination of a pan for the recep- 100

- tion of combustible material for use under a fire-grate, with a rotating arm carrying a match-holder, and a striking-surface on the pan, substantially as set forth.
- 5 2. The combination of a pan to receive combustible material, and having a striking-surface, with an arm carrying matches, a spring to rotate the arm, and a retaining-catch for the arm.
- 10 3. The combination of the pan to receive combustible material, and having a striking-surface and a bottle-support, with a rotating arm carrying matches, and fingers to break the bottle, substantially as set forth.
4. The combination of the pan to receive 15 combustible material, with a rotary arm carrying a match-holder, and a yielding striking-surface on the pan, substantially as set forth.
- In testimony whereof I have signed my name to this specification in the presence of two sub- 20 scribing witnesses.

JOSHUA O. HOWE.
